UNITED STATES PATENT OFFICE.

CHARLES E. DIEHL, OF DES MOINES, IOWA.

MEANS FOR MOISTENING THE AIR USED IN EXPLOSION-ENGINES.

1,123,114.

Specification of Letters Patent. Patented Dec. 29, 1914.

Application filed October 28, 1908. Serial No. 459,930.

To all whom it may concern:

Be it known that I, CHARLES E. DIEHL, a citizen of the United States, residing at Des Moines, in the county of Polk and State of Iowa, have invented certain new and useful Improvements in Means for Moistening the Air Used in Explosion-Engines, of which the following is a specification.

My invention has reference to means for moistening the air used in explosion engines, and its object is to secure a constant artificial moistening of the air as distinguished from the natural and variable moistening thereof. This is accomplished by providing means whereby natural moisture is eliminated and the proper definite quantity of moisture necessary for successful running of the engine is added to the dried air before it reaches the carburetor.

In the drawings: Figure 1 is a side view of an explosive engine cylinder with my moistening device applied thereto. Fig. 2 is a cross section of the same on the line 2—2 of Fig. 1. Fig. 3 is a longitudinal sectional view of a portion of the cylinder and the moistening chamber. Fig. 4 is a perspective view of the moistening chamber broken away. Fig. 5 is a transverse sectional view of a modified form of moistening chamber.

Similar reference numerals designate corresponding parts in all the figures of the drawings.

In the drawings, 2 designates the cylinder of an explosive engine of any ordinary or desired character, and 3 a moistening chamber consisting of a casing formed of four walls, open at the bottom but closed at the top by a perforated cover or plate 4, this plate being perforated for the inlet of air through perforations 5.

6 designates a water inlet pipe leading from any suitable source of supply, as a tank 7. This pipe is preferably provided with a regulating valve 8 of any desired character, which shall supply a definite quantity of water to a sheet of fibrous material 9 which is supported within the casing 3. While I have shown only one pipe 6 whereby the water may be conducted from the supply pipe to the fibrous sheet 9, I wish it understood that I may use a plurality of pipes 6 opening into various portions of the chamber 3, in order to moisten this fibrous

sheet over its entire surface so that every particle of air passing through the perforations in the casing will be obliged to pass over and through the moistened surface of the fiber.

It will be seen that the layer of fibrous or spongeous material 9 divides the chamber 60 into two parts, an upper and a lower, and preferably I use a partition of wire network upon which the sheet or fiber is laid. This partition 10 may be made so as to be readily removable from the casing and to 65 permit the introduction of fresh wicking or other fibrous layer if desired. The portion of the casing below the wicking or fibrous layer is connected by a conducting channel 11 to any suitable carburetor 12. I do not 70 wish to be limited in this regard, but I have shown the cylinder 2 of the engine as being grooved or channelled, the grooves or channels extending around the cylinder from a point beneath the casing 3 to a point where 75 the groove or channel connects with a conducting pipe 13 leading to the carburetor 12. This groove or channel is covered by a semi-circular or half pipe 14.

By reason of the particular arrangement 80 of the outlet conduit for the moistened air, it is necessary to carefully gage the supply of water to the air-moistening device, so that at no time will water flow from the bottom of the casing into the pipe 14. In 85 actual practice, the supply of water is so proportioned that the air passing through the moistening device wholly absorbs the water and none drips through the porous sheet 9 in the bottom of the casing. The advantage of this is that comparatively little water is required so that the device is especially adapted for automobile service without requiring a large storage tank for water. If water should be supplied in excess of the capacity of the air to take up moisture, the pipe 14 would become flooded and form a trap which would render the engine inoperative, either by sucking water into the carburetor or by preventing the 90 necessary quantity of air to be drawn through the carburetor and into the engine for producing explosions.

The purpose of conducting the moistened air around the cylinder is to heat the same 105 prior to its introduction into the carburetor

and to more thoroughly vaporize the water contained in suspension in the air. In the carbureter of course the moistened air is mixed with the proper quantity of hydro-
5 carbon to form the usual explosive mixture. I may of course use any form of carbureter and the carbureter and its connection to the engines do not form any part of my present invention. I do not wish to be limited to
10 the form in which the fibrous material is applied within the casing or to the material itself. I preferably use wicking supported on copper gauze but I may use a spongyous material or a relatively stiff porous material,
15 such as porous terra-cotta. Any material which will allow water to be readily distributed throughout its mass, and which will permit the passage of air and the taking up of this moisture by the air, is within the
20 terms of my invention. As a means for readily removing the fiber within the casing, I have shown the cover of the casing as hinged thereto, but I do not wish to be limited to the exact form shown as the form of
25 the moistening chamber might be varied in many ways.

In Fig. 5, I show another form of my device, in which my process is carried a step farther than in the form previously described. The object of this device is to entirely eliminate the natural moisture contained in the air, to dehydrate the air, and then to supply a definite content of moisture to the air previous to its introduction into the carbureter. To this end I form my moistening chamber in two portions, in one of which any suitable dehydrating material, such as chlorid of calcium or calcium oxid is supported. The air is directed across or
30 through these dehydrating materials, and then after having had its natural moisture entirely eliminated, is brought into the second chamber and there passed through moistened fiber as previously described and
35 conducted to the carbureter.

In Fig. 5, 15 designates the casing of my device which is in the same form but somewhat larger than the casing shown in Fig. 4. It is transversely divided by a partition
50 which is perforated as at 17 above the line of the moistening fiber 18. The chamber 19, formed by dividing the casing by the partition 16, is the dehydrating chamber and contains a series of trays 20 formed prefer-
55 ably of copper gauze on which is supported any suitable compound or material which has an affinity for water, and which will absorb the moisture from the air. I do not wish to be limited to the exact materials used, though I have indicated chlorid of calcium or calcium oxid. The chamber 19 is provided with a series of air inlet openings 21 and with a baffle plate 22 whereby the air is forced downward and into contact

with all the series of screens and all of the 65 dehydrating material. After passing the dehydrating material, the air enters the moistening chamber of the casing through the opening 17. This portion of the casing is precisely similar to that previously de-
70 scribed, and contains the perforated sup-
porting tray or partition 23 supporting the wicking or other porous layer 18. A water tube 25 is provided with a controlling valve
75 26, and a conducting channel 27 leads from the space below the moistening fiber to any desired carbureter, preferably in its passage
80 passing around the engine cylinder so as to heat the moistened air.

I have found in practice that supplying 80 moisture at all times artificially to the air entering the carbureter has an extremely good effect upon the efficiency of the engine, and that a machine supplied with an air moistening device, such as I have described, 85 is not subject to variations in efficiency due to the variations of humidity in the atmosphere but that means are provided whereby a constant of efficiency is secured under practically all conditions. I have further 90 found that still better results can be ob-
tained by the elimination of all natural moisture and then the addition of just the proper amount of moisture needed for per-
95 fect operation. By this further step of my method, I do away with all variable or acci-
dental factors. There is never any acci-
dental chance of getting too much or too little moisture, but the said machine will attain maximum of efficiency under all weather 100 conditions whether the exterior air is sat-
urated with moisture or whether it is ex-
tremely dry.

While I have shown a form of device which is exceedingly simple, which may be 105 easily applied to any engine cylinder, and which is thoroughly effective in actual prac-
tice, I do not wish to be limited to the pecu-
liar construction shown nor to the arrange-
ment of parts in relation to the engine. It 110 will be seen that my method is in line with the best practices in other arts, in that it substitutes for a natural and variable factor, an artificial and definite factor always under control to give the best results.

Having thus fully described my invention, what I claim as new, and desire to secure by Letters Patent, is:—

1. The combination in an internal com-
bustion engine having an air supply, a fuel 120 supply, and a mixing chamber therefor, of
means arranged intermediate the air sup-
ply and the mixing chamber to humidify
the air to a predetermined degree of satura-
tion comprising a dehydrating device and 125 a humidifying device interposed suc-
cessively in the path of the air to a point of
admixture with the fuel, said devices mount-

- ed in close juxtaposition to the cylinder and heated thereby.
2. The combination in an internal combustion engine having an air supply, a fuel supply, and a mixing chamber therefor, of means arranged intermediate of the air supply and the mixing chamber to humidify the air to a predetermined degree of saturation and comprising a casing fitted to the cylinder and having a chamber through which the air passes, trays in said chamber supporting a dehydrating material, a chamber through which the air passes from the dehydrating chamber and containing a porous material, means for supplying water to the porous material, and means for conducting the air after its passage through the wet porous material to the mixing chamber for admixture with the fuel.
3. The combination with a cylinder and carbureter of an explosive engine, of an air moistening device therefor comprising a casing fitting around and over the cylinder, said casing having therein a transverse partition parallel with the cylinder and formed of porous material, said casing above the partition being provided with air openings and with means for constantly supplying moisture to the porous partition, the casing below the porous partition being connected to said carbureter.
4. The combination with the cylinder and the carbureter of an explosion chamber, of an air moistening device therefor comprising a casing fitting against the cylinder and having end and side walls, a cover forming the top of the casing and perforated for the admission of air, a partition dividing the casing and substantially parallel with the bottom thereof, said partition being formed of porous material, a water pipe entering the top of the casing to supply water to the porous partition, and a conduit between the bottom of the casing and the carbureter.
5. An explosion engine provided with a carbureter adapted to contain a fuel supply, and means for supplying air to said carbureter in contact with the fuel therein including a casing provided with an interior porous partition dividing the casing into two chambers, the chamber on one side of the partition being in heat receiving relation to the engine and the chamber on the other side of the partition being in communication with the atmosphere, means for supplying water to the porous partition in determinate quantities, and air conveying connections through the carbureter from that chamber which is in heat receiving relation to the engine.
6. The combination with a cylinder and carbureter of an explosive engine, of a casing secured to the cylinder, said casing being open at the bottom in contact with the cylinder walls, and having therein a partition formed of porous material arranged substantially parallel to the bottom of the casing and dividing the casing into two portions, means for supplying moisture to the porous partition, and a conduit leading from the casing below the partition, extending around the cylinder and thence extending to said carbureter.
7. The combination of an explosive engine, and a carbureter from which a vapor charge of air and hydro-carbon is drawn into the cylinder during the suction stroke, with a device for moistening the air supplied to the carbureter, said device comprising a casing open at one portion and arranged on the cylinder to close the said open portion by the latter, a porous partition dividing the casing into separate air compartments, means for admitting atmospheric air to one of the compartments, means for connecting the other compartment with the carbureter, and means for supplying water to the partition at such a rate as to be absorbed by the air passing through the partition as fast as the water is supplied to the latter.
8. The combination of an explosive engine, a carbureter connected therewith, an air moistening device, means for connecting the device with the carbureter to cause air to be drawn successively through the device and carbureter by the suction of the engine, means for positively heating the moistened air before reaching the carbureter, and means for supplying water to the device continuously and in such a quantity as to be wholly evaporated and absorbed by the air previous to its contact with the hydro-carbon in the carbureter.
9. The combination of an explosive engine, with a carbureter, and an air moistening and heating device so connected with the carbureter that air is drawn through the device before admixture with the hydro-carbon in the carbureter by the suction of the engine and fitted directly to the engine whereby the heat from the engine preheats the moistened air before its admission to the carbureter.
10. The combination with a cylinder and a carbureter of an explosive engine, of a casing fitted to the cylinder, a conduit leading from the casing to the carbureter, means for admitting air to the casing, means for dehydrating the admitted air, and means for subsequently supplying moisture to the air before its admixture with the hydro-carbon in the carbureter.
11. The combination with a cylinder and a carbureter of an explosive engine, of a casing fitted to the cylinder, a conduit leading from the casing around the cylinder to

the carbureter, means for admitting air to the casing, means for dehydrating the admitted air, and means for subsequently supplying moisture to the air before its admixture with the hydro-carbon in the carbureter.

In testimony whereof I affix my signature in presence of two witnesses.
